UNITED STATES PATENT OFFICE

2,588,984

CONVEYER CARRIER BAR

Chester S. Kubisiak, Wisconsin Rapids, Wis.

Application May 9, 1949, Serial No. 92,195

2 Claims. (Cl. 263—8)

1

This invention relates to novel and useful improvements in conveyor carrier bars.

An object of this invention is to compensate for expansion and contraction of the conveyor operating members and tracks in the carrier bars, particularly when the carrier bars and the conveyor elements are used in connection with a high temperature zone by means of an extensible carrier bar which is attached to a pair of spaced conveyor members such as chains and which has a resilient seat thereon whereby the work may be supported.

Other objects and features will become apparent to those skilled in the art, in following the description of the preferred form of the invention, illustrated in accompanying drawings, wherein:

Figure 1 is a perspective view of a fragmentary portion of an endless conveyor with the improved carried bar thereon;

Figure 2 is a plan view of the structure shown in Figure 1;

Figure 3 is a sectional view taken on the line 3—3 of Figure 2 and in the direction of the arrows;

Figure 4 is a transverse sectional view taken substantially on the line 4—4 of Figure 3 and in the direction of the arrows; and

Figure 5 is a sectional view taken substantially on the line 5—5 of Figure 3 and in the direction of the arrows.

In conventional conveyor equipment which is used in high temperature regions such as in a furnace or oven, the rails and supports for the conveyor contract and expand due to the intense heat. Warping is the necessary result in the carrier bars.

In the present invention, this expansion and contraction is compensated for by means of an extensible carrier bar having improved means thereon serving as a work support. The conventional conveyor operating members, as the chains 10 and 12, respectively, are illustrated to show the environment of the apparatus. A tube 14 is supplied with a rod 16 which may also be tubular but of a smaller outside diameter. There is an extensible or telescoping relationship between the rod 16 and the tube 14.

At one end of the rod 16 there is means for attachment with the chain 12. This means consists preferably of a lug 18 welded or otherwise fixed to one or more links of the chain 12 having an opening therein. A screw 20 or other equivalent fastener is passed through this opening and also through an opening in a plate 22 which is fixed to the rod 16.

At the opposite end of the carrier bar, there is a similar structure provided including a lug

2

24 fixed to a link of the chain 10 and a plate 26 fixed to the end of the tube 14. This attaches the opposite end of the device to the chain 10.

Substantially similar brackets 30 and 32, respectively, are fixed at the ends of the sleeve 14 and have the ends of the spring 34 secured thereto. This spring is stretched between the brackets 30 and 32, thereby forming a seat for the work which is to be conveyed. This resilient seat is all that is necessary for holding the articles.

Spring supports 38 and 40, respectively, are fixed to the sleeve 14 and on the upper surface thereof. These spring supports are preferably semi-cylindrical in shape so that they embrace a portion of the spring leaving the upper part thereof exposed.

Obviously, any number of spring supports may be used as found necessary or desirable from an engineering standpoint.

20 It is apparent that variations may be made without departing from the spirit of the invention.

Having described the invention, what is claimed as new is:

25 1. For use with a pair of spaced conveyor chains, a carrier bar comprising a pair of longitudinal elements connected together for extensible movement with means secured to each element for fastening to said conveyor chains, 30 a spring constituting a resilient seat supported by one of said elements, said spring being arranged parallel to said elements, and at least one spring support for said spring secured to said one of said elements.

35 2. In a conveyor for use in a high temperature zone, a carrier bar comprising a tube, a rod slidably disposed in said tube, means disposed at one end of said rod and said tube respectively for securing said tube and said rod to conveyor operating chains, a spring extending longitudinally of said tube and constituting a resilient seat, said spring being secured to said tube, and a spring support secured to said tube extending partially around said spring.
